The ornamental design for a door for dialysis machine, as shown and described.

DESCRIPTION

FIG. 1 is a perspective view of the door for dialysis machine;
 FIG. 2 is a front elevational view thereof;
 FIG. 3 is a left side elevational view thereof;
 FIG. 4 is a right side elevational view thereof; and,
 FIG. 5 is a top plan view thereof.

The broken lines in the drawing views are included for the purpose of illustrating portions of the door for dialysis machine that form no part of the claimed design.
